(57) **CLAIM**

The ornamental design for an iron type head for a golf club, as shown and described.

DESCRIPTION

FIG. 1 is a perspective view showing the front and toe end sides of an iron head type for a golf club embodying the new design;

FIG. 2 is a front elevational view thereof;

FIG. 3 is a toe end elevational view thereof;

FIG. 4 is a heel end elevational view thereof;

FIG. 5 is a rear elevational view thereof;

FIG. 6 is a top plan view thereof; and,

FIG. 7 is a bottom plan view thereof.

The broken line depiction of a faceplate groove pattern is for illustrative purposes only and forms no part of the claimed design.
